UNITED STATES PATENT OFFICE.

ERNST JENSEN, OF MUNICH, GERMANY.

PRINTING-MACHINE.

SPECIFICATION forming part of Letters Patent No. 697,089, dated April 8, 1902.

Application filed May 7, 1900. Serial No. 15,869. (No model.)

To all whom it may concern:

Be it known that I, ERNST JENSEN, a subject of the King of Saxony, residing at Munich, Bavaria, Germany, have invented certain new and useful Improvements in Printing-Machines, of which the following is a specification.

In the accompanying drawings illustrative of a machine constructed in accordance with my invention, Figure I is a vertical longitudinal sectional view; Fig. II, an end elevation; Fig. III, a top plan view with part of the handle broken away; Fig. IV, a plan view of the guide-rail on a reduced scale, and Fig. V a transverse sectional view thereof.

Like letters of reference mark the same parts in all of the figures of the drawings.

The machine is provided with a hollow cylinder *a*, having interior screw-threads in its ends to receive screw-plugs *d* and *e*, which latter have threaded openings in their outer ends to receive journals *g* and *h*. A pin *w* enters the edge of cylinder *a* and of a cylinder *b* to prevent them from moving upon each other. The design-roll *c* is carried by a hollow shell or double cylinder *x*, mounted on cylinder *b*, the design-roll being a cylinder of felt with or without the design branded or burned in or on its periphery, or of soft gum, celluloid, hard gum, metal, or other suitable material, while the shell *x* is elastic and filled with air and is to be removed or replaced with the design-roll. In the surface of cylinder *c* is a small semi-annular groove *y* to receive wards on the steel sheet of the guide-rail *u*, Fig. IV.

The design-roll when of celluloid, hard gum, metal, or the like serves for the production of cameo or intaglio designs on soft moist cement, plaster, asphalt, or the like.

The screw-plug *e* has formed with it a disk *e'*, which serves as the head of said screw-plug and holds the design-roll against end-wise movement, while a similar disk-head *d'* on the screw-plug *d* serves the same purpose at the opposite end of the design-roll. The disk *d'* has formed integral with it a second disk *d''*, partially separated from it by an annular space or groove of a width and depth conforming to the narrow part *u²* of the guide-rail, Fig. V.

The journals *g* and *h* are mounted in bearings in a bow *f* and may be readily and easily placed in or removed therefrom by simply unscrewing them from the plugs *d* and *e*. 55

K indicates the reservoir for ink or color, which is secured to lateral projections from the bow *f* by means of screws *s* and *t*, which enter slots in said projections, whereby the distance of the reservoir from the axis of the design-roll may be regulated. (See Figs. I and II.) The reservoir is longitudinally slotted in its bottom to permit of the projection therethrough of an inking-roll *m* into contact with the design-roll, said roll *m* being journaled at one end in the head *l* of the reservoir and at its opposite end in a disk *o*, seated in the opposite end of the reservoir and covered by the cap or head *p*, said disk *o* being secured by a pin *z* and provided above 70 the roll with an opening through which to fill the reservoir when the cap or head *p* is removed. The steel sheet *u³*, secured upon the guide-rail *u*, forms the bottom of the groove *u'* and has formed upon its edge wards *u⁴*, 75 while the part *u²* has openings or notches *u⁵*. When the machine is to be started, it is placed upon the guide rail or disk *d'* in groove *u'* and part *u²* in the annular groove between disks *d²* and *d''* and with pin *v* resting in any one of 80 the notches or openings *u⁵* of guide-rail *u*, so that the device will roll on the guide-rail away from or toward the handle thereof, as desired, one of the wards *u⁴* entering a groove *y* and the pin *v* entering one of the notches 85 *u⁵*, whereby the design-roll is kept from sliding and held clear of the ink-roll during its movement in its either direction.

Having thus fully described my invention, what I claim as new, and desire to secure by 90 Letters Patent of the United States, is—

1. In a printing-machine, the combination with a hollow cylinder having interiorly-threaded ends, of screw-plugs threaded in said ends, a bow, and journals mounted in bearings therein and threaded into the outer ends of the screw-plugs, substantially as described. 95

2. In a printing-machine, the combination with a hollow cylinder having interiorly-threaded ends, of screw-plugs threaded in said 100 ends and having threaded openings to receive journals, said screw-plugs being also provided

with disk-heads and a design-roll held in place between said heads, substantially as described.

3. In a printing-machine, the combination with a hollow cylinder, of screw-plugs threaded in the ends thereof, journals threaded in said plugs, a bow having bearings for said journals, and projections radially slotted, and screws passing through the reservoir-shell 10 and into the radial slots, substantially as described.

4. In a printing-machine, the combination with the design-roll and its supports, com-

prising disks d^1 and d^2 with the space between them, of the guide-rail comprising parts u and u^2 with slot u' between them, the steel sheet u^3 with wards u^4 , and the part provided with groove y , substantially as described.

In testimony that I claim the foregoing as my invention I have signed my name in presence of two subscribing witnesses.

ERNST JENSEN.
